[57] CLAIM

The ornamental design for a flexible insulation device for beverage container with handle, as shown and described.

DESCRIPTION

FIG. 1 is a perspective view of the flexible insulation device for beverage container with handle, showing my new design;

FIG. 2 is a front elevational view thereof;

FIG. 3 is a left side elevational view thereof;

FIG. 4 is a right side elevational view thereof; and

FIG. 5 is a top plan view thereof, the side opposite being a mirror image; and,

FIG. 6 is a perspective view of the flexible insulation device for beverage container with handle of FIG. 1, shown in a collapsed state.

The broken line showing of a container in FIG. 1 is for illustrative purposes only and forms no part of the claimed design.
